UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed December 23, 1920. Serial No. 432,798.

To all whom it may concern:

Be it known that I, LIONEL M. WOOLSON, a citizen of the United States, and resident of Detroit, Wayne County, State of Michigan, have invented certain new and useful Improvements in Hydrocarbon Motors, of which the following is a specification.

This invention relates to hydrocarbon motors and particularly to the mixture conduit and the heating means therefor.

One of the objects of the present invention is to provide a novel form of intake pipe or conduit for efficiently handling the mixture between the carburetor and the motor.

Another object of the invention is to provide a novel form of intake conduit with an efficient heating device for the mixture passing therethrough.

Other objects of the invention will appear from the following description taken in connection with the drawings, which form a part of this specification, and in which:

Fig. 1 is a front elevation and part vertical section of a hydrocarbon motor embodying the invention;

Fig. 2 is a section taken at right angles to Fig. 1, substantially on the line 2—2 of Fig. 1;

Fig. 3 is a cross section on the line 3—3 of Fig. 1; and

Fig. 4 is a cross section on the line 4—4 of Fig. 1.

Referring to the drawings, 10 represents one of the cylinders of a hydrocarbon motor and 11 and 12 are two intake pipes or conduits leading to the intake valves of the motor. A carburetor 13, of any suitable construction, is adapted to supply mixture to the pipes 11 and 12 and throttle valves 14 and 15, connected by gearing 16, are adapted to control the passage of the mixture through the two outlet passages 17 and 18 from the carburetor.

An intermediate pipe or conduit 19 forms the connection between the passages 17 and 18 of the carburetor and the pipes 11 and 12 above referred to. This intermediate pipe has its middle portion in the form of a single chamber 20 and its inlet end is divided by a partition 21 so that there are

two inlet passages 22 and 23 which connect with the outlet passages 17 and 18 respectively of the carburetor. The outlet end of the intermediate pipe 19 is also divided by 55 a partition 24, thus forming two outlet passages 25 and 26 which communicate respectively with the pipes 11 and 12.

For the purpose of nicely connecting the carburetor to the intake pipes 11 and 12 60 and at the same time retaining the float chamber of the carburetor at one side thereof so that the level in the carburetor nozzle will not vary as the motor is tilted upwardly or downwardly at its front end, the intermediate pipe 19 is so formed that the axes of passages 22 and 23 are in a plane which is at right angles to a plane passing through the axes of passages 25 and 26. This twisting in the arrangement of these passages is 65 made possible partly by reason of the formation of the pipe 19 with a single chamber in its middle portion.

Thus, if the two nozzles of the duplex carburetor were arranged transversely of 75 the engine instead of longitudinally thereof as in the drawing, which would be the case if the intermediate pipe 19 did not provide for the twist, one of the nozzles would be farther away from the float chamber than 80 the other and would thereby receive more or less fuel than the other when the engine is tipped sideways, or if the float should be arranged forward or aft of the transversely arranged nozzles then the engine would receive more or less fuel depending upon 85 whether the engine was pointed upwardly or downwardly. By arranging the nozzles and float chamber as shown these objections are overcome.

For the purpose of heating the mixture as it passes through the intake pipe 19, a combustion heater is provided and mounted upon the intake pipe. It is shown in the form of a jacket 27 surrounding part of the 95 intake pipe 19 and having two outlets 28 into the passages 22 and 23. This jacket 27 forms a heating chamber, the upper part of which is continued by a combustion chamber 29 formed in a burner body 30 which is secured to the jacket 27 as by bolts 31. The combustion chamber 29 has an observation 100

window 32 and a spark plug 33. Its valved inlet is shown at 34, the adjustable valve 35 governing the amount of mixture which may enter the combustion chamber.

- 5 Mixture is supplied to the combustion heater in the form shown by a pipe 36 which connects with a small carburetor 37 shown as mounted in the float chamber 38 of the carburetor 13 above referred to.
- 10 From the above description it will be seen that when the throttle valves 14 and 15 are closed or nearly so and the motor is idling, the suction above the throttle valves will cause a depression in the jacket 27 whereby mixture is drawn from the auxiliary carburetor 37 through the pipe 36 to the combustion chamber 29. The mixture is there exploded by the spark plug 33 and a certain amount of heat is transferred to the mixture in the pipe 19 through the intervening wall. The products of combustion pass downwardly through the jacket 27 and through the ports 28 into the passages 22 and 23 of the pipe 19. This
- 15 hot burnt gas mixes with the mixture and heats it on the way to the motor, thereby supplying the motor with a hot dry mixture when idling. As the throttle valves are open and the suction above the throttle 30 is consequently lessened, the amount of heat produced by the combustion heater is reduced, and of course the heat is not then so much needed because the motor itself supplies sufficient heat for properly handling
- 20 the charge.

It will be understood that various forms of the invention other than those described above may be used without departing from the spirit or scope of the invention.

Having thus described my invention, what I claim and desire to secure by Letters Patent is:

1. In a hydrocarbon motor, the combination with a carburetor having two mixture outlet passages, interconnected throttle valves for said passages, and a pair of mixture conduits connected to the motor, of an intermediate intake pipe having a portion thereof in the form of a single chamber and having one end portion divided to form two conduits for connection to the two mixture outlet passages of the carburetor above said throttle valves, and said intermediate pipe having its other end portion connected to said mixture conduits, of a heater device of combustion form mounted upon and forming a jacket for a portion of the wall of the single chamber part of said intermediate pipe, and an outlet means for said combustion heater leading from said heater to said two conduits above said throttle valves.

2. In a hydrocarbon motor, the combination with a carburetor having two outlet passages, and two intake pipes having their inlet ends arranged in parallel, of an intermediate intake pipe having two inlet passages connected to the outlet passages of said carburetor and having two outlet passages connected to the inlet ends of said first intake pipes, the axes of the inlet passages of said intermediate pipe being in a plane at right angles to a plane passing through the axes of the outlet passages thereof.

In testimony whereof I affix my signature.

LIONEL M. WOOLSON.
